UNITED STATES PATENT OFFICE.

LUDWIG SCHODDER, OF HERFORD, GERMANY, ASSIGNOR TO CARL WITTENBORG, OF HERFORD, WESTFALIA, GERMANY.

SMOKE-DISCHARGING MEANS FOR LOCOMOTIVES AND THE LIKE.

Application filed October 4, 1922. Serial No. 592,440.

To all whom it may concern:

Be it known that I, LUDWIG SCHODDER, railroad engineer, a citizen of Germany, and a resident of 23 Bündnerstrasse, in the city of 5 Herford, in Westfalia, Germany, have invented certain new and useful Smoke-Discharging Means for Locomotives and the like, of which the following is a specification.

10 This invention has reference to improvements in means of discharging the smoke from locomotives or from similar coal fed engines or moving boilers to the outside, and thereby preventing the discharge of the 15 smoke into the sheds or enclosures in which such engines or boilers are housed, and it particularly refers to novel means of tightening connection of the hood or similar appliance which is exchangeably mounted 20 upon the end of the locomotive or boiler chimney, and to improved means of handling and operating the same. In devices of this kind, as heretofore in use a hood, funnel or the like is made to descend upon 25 the upper end of the chimney of the locomotive or the like housed in a shed or the like, by means of rope, chain or the like, the hood or funnel being thereby seated upon the said chimney and causing the smoke to 30 be discharged into the surrounding casing from which it is drawn off into the chimney and into the atmosphere by a suitable flue or other passage. In order to prevent destruction or injuring of the locomotive or 35 of the hood or funnel, when the locomotive is run out of the shed, it has been usual to mount the hood, funnel or the like, so as to be capable of swinging movement in the direction of travel in addition to its vertical 40 reciprocating movement, while the weight of said hood or the like has been balanced by a counter weight suspended from chains or ropes, and guided on rollers in the ordinary manner, a special additional rope being em- 45 ployed for the raising and lowering of the hood, funnel or similar smoke escape.

This invention is intended to improve the means of suspension and the automatic return of the said smoke escape conduits into 50 the inoperative position, and to provide improved means for the guiding of said conduit in the surrounding casing, and for the tightening of the joint at its points of connection with the locomotive chimney, and 55 for the prevention of the accumulation of

soot and the like and the consequent choking up of the said smoke escape conduit.

With these and other objects in view only one flexible connection by rope or the like is employed for connecting the smoke conducting means with the counter weight and for the raising, lowering and rendering inoperative of the said conducting means, the 60 said flexible connection being provided with an automatically operating locking member. 65 The casing surrounding said conducting means is laterally enlarged, and at its bottom it is provided with two substantially semi-circular flaps or lids adapted to yield upon the swinging movement of the smoke 70 conducting means, hood, funnel or the like, preferably only one of said lids being vertically oscillated by the swinging of the hood.

My invention will be more fully explained by the aid of the accompanying drawing 75 showing by way of example a form of embodiment of the principles of the invention in Figure 1 as a side view of the entire device with connections. Figure 2 is a horizontal section through the lower portion of 80 the funnel or the like and through the casing on the line A—B of Figure 1. Figure 3 is a fractional diagrammatic sectional view on the line C—D of Figure 2; and Figure 4 is a horizontal section through the 85 counter weight and its guiding means.

The hood *f* is funnel shaped, and consists of a tube with lower substantially spherical enlargement which latter is adapted to fit upon the locomotive chimney *s*. Upon its 90 outer surface the funnel *f* is provided on both sides with preferably U-shaped guides *n* into which studs *m* rigidly secured to the surrounding casing *e* are projectingly engaged. The casing *e*, as shown in Figures 95 1 and 2 is laterally enlarged on both sides, and as a bottom closure it is provided with two substantially semi-circularly recessed lids or flaps *h*. To the funnel-shaped casing *e* a smoke escape conduit *p* is connected 100 which leads into the stationary chimney not shown. The smoke conduit may, of course, have any direction whatever. Thus, for example the said conduit may lead directly upwards into an individual smoke chimney, 105 or into a smoke escape passage in common to a plurality of smoke discharging funnels or the like. The top portion of the funnel *f* is connected to a chain or rope *c* which is passed on guide rollers and connected to the 110

counter weight o which is vertically reciprocated in a suitable guide q . The counter weight o is heavier than the funnel f , so as to retain it normally in the raised position (Figure 1). If the locomotive or the like has been run into the shed or other building containing the smoke catching and directing device, so that the locomotive chimney is placed vertically below the funnel f , the latter must be lowered upon the locomotive chimney by raising the counter weight o . This is effected by means of a hand wheel d and a gear wheel connected therewith and engaging with a rack bar provided upon the counter weight. Any other lifting means may, of course, also be employed.

At the upper end of the counter weight o a lever a is mounted which is loaded at one side by the weight k and is fulcrumed at the point g . The lever a is integral with the pawl i adapted for engagement with a rigidly mounted rack bar b . Upon raising the counter weight o by means of the hand wheel d until the funnel f becomes seated upon the locomotive chimney s , the locking lever a, i remains at first out of engagement with the rack bar b . But upon continuing to raise the counter weight o the rope or chain c is released from tension, and is caused to sag, and in consequence thereof the locking lever a, i is free to be swung laterally by the action of the one-sided load k , and the pawl i may now become engaged with one of the teeth of the rack bar b , as indicated in dotted lines. This causes the counterweight o to become suspended from the rack bar and thereby to be thrown out of operation. The smoke escaping from the locomotive chimney is discharged through the funnel f into the casing e and thence through the channel or flue p into the stationary chimney. If it is desired to interrupt the escape of the smoke and to disconnect the locomotive chimney from the funnel, it is only necessary to disengage the locking pawl i and the locking lever a ; the counter weight o becomes then free to operate, and lifts the funnel f into its highest position.

The device is, moreover, adapted for automatic operation. Thus, if an engine is run out of the shed in the direction indicated by the arrows the chimney s will carry the funnel f with it to a certain extent, in view of the fact that the funnel is free to oscillate on the studs m , and in view of the corresponding lateral enlargement of the casing. During this swinging movement the lower closing flaps or lids h of the funnel casing e are swung out of the way, and during their movement any accumulated soot will be simultaneously discharged. After the engine has been run out to such a distance that it is out of engagement with the funnel f the funnel is no longer supported upon

the locomotive chimney, and by its own weight it causes the tensioning of the rope or chain on which it is suspended, and in consequence thereof the locking pawl a, i is moved into the position of disengagement, so as to lift the pawl i out of the teeth of the rack bar b . At this moment the counter weight o which is heavier than the funnel f will operate and raises the funnel into the inoperative position. The device according to my invention presents a great many other advantages. As a result of its mode of operation the funnel will always be compelled to be perfectly lowered into close contact with the locomotive chimney, so as to insure the required tight connection for the exclusion of the leaking of smoke, because, unless the funnel f is completely lowered, so as to raise the counter weight to the required height, the locking by the pawl lever a, i cannot take place, inasmuch as this locking lever can only be operated, provided the load is taken off the flexible connection between the funnel f and the counter weight o , that is to say, when the funnel rests upon the locomotive chimney with its full weight. No similar perfect sealing of the connecting joint with the use of only one rope or flexible connection, as far as I am aware, has ever been produced in the previous smoke catching and conducting means of the kind referred to.

It is obvious that my invention is capable of various modifications and alterations as the conditions of its application may require. 100

I claim:—

1. In a smoke catching device, in combination a horizontally movable chimney, a vertically reciprocable and oscillatable hood, adapted to be seated on the top of said chimney, a counterweight for said hood, and a flexible connection between said hood and said weight, and tiltable locking means intermediate said weight and said flexible connection. 105

2. In a smoke catching device, in combination, a horizontally movable chimney, a vertically reciprocable open-ended hood, adapted for engagement with the top of said chimney, and mounted for swinging movement in a vertical plane, an over-balancing counterweight, and a flexible connection between said counterweight and said hood, a tiltingly mounted locking member intermediate said weight and said flexible connection, and a stationary member, engageable with said locking member in a certain vertical position of said counterweight, and means for reciprocating said counterweight. 115

3. In a smoke catching device, in combination, a horizontally movable chimney, a vertically reciprocable hood, adapted for engagement with the top of said chimney, a surrounding casing spacedly enclosing part 120

- of said hood, and means on said hood for the swinging suspension of said hood on said casing, a smoke discharge passage on said hood, an overbalancing counter weight, 5 and a flexible connection between said counter weight and said hood, a tilttable locking member on said flexible connection, means of vertically reciprocating said counter weight, and a stationary locking member, 10 adapted for engagement with said tilttable locking member in the complete seating position of said hood upon the top of said chimney.
4. In a smoke catching device, in combination, a horizontally movable chimney, a vertically reciprocable open-ended hood substantially in line with said chimney, and adapted for seating engagement with the top of said chimney, a horizontally laterally enlarged casing, spacedly surrounding said hood, and means to swingingly suspend said hood from said casing, smoke discharging means on said casing, vertically swingingly mounted closing flaps at the bottom 25 of said casing and around said hood, an overbalancing counter-weight, a flexible connection between said counter-weight and said hood, a tilttable locking member on said flexible connection, means for vertically reciprocating said counter-weight, and a stationary rack bar, engageable with said locking member in the raised position of said counter weight.
- 35 5. In a smoke catching device, in combination, a horizontally movable vertical chimney, a substantially tubular downwardly enlarged hood, adapted for seating engagement with the top of said chimney, a casing, spacedly 40 surrounding part of said hood and laterally enlarged, means to swingingly suspend said hood from said casing, a substantially annular, sectional closing bottom, covering the space between said hood and said casing, the sections of said bottom being swingingly suspended below the point of suspension of said hood, and allowing of inward swinging movement of at least one of said sections upon the swinging of said hood, smoke discharging means on said casing, a counter-weight for said hood, and a flexible connection between the weight and said hood, and tilttable locking means on said flexible connection.
6. In a smoke catching device, in combination, a horizontally movable vertical chimney, a substantially tubular, downwardly substantially invertedly funnel-shaped hood, adapted for seating engagement with the top of said chimney, a laterally enlarged, substantially rectangular, funnel shaped casing, spacedly surrounding part of said hood, smoke discharging means on said casing, means of swingingly suspending said hood on said casing, closing flaps constituting the bottom of said casing and swingingly mounted below the point of suspension of said hood, an overbalancing counter-weight, means to vertically reciprocate said weight, a flexible connection between said weight 70 and said hood, and a tilttable locking member on said flexible connection, and a stationary rack bar, engageable with said locking member in the raised position of said counter weight.
7. The combination with a smoke hood and the like, an overbalancing counter-weight and a flexible connection between said counter-weight and said hood, of a locking pawl tiltingly pivoted to the top 80 of said counter-weight, and in operative relation to said tilttable connection, raising and lowering means for said counter-weight, and a stationary rack bar with which said locking pawl is engageable in the raised position of said counter-weight.

LUDWIG SCHODDER.
